UNITED STATES PATENT OFFICE.

EDWIN O. TOWNSEND, OF NEW YORK, N. Y.

DESIGN FOR A MONUMENT.

41,062.

Specification for Design. Patented Dec. 27, 1910.

Application filed November 1, 1910. Serial No. 590,248. Term of patent 7 years.

To all whom it may concern:

Be it known that I, EDWIN O. TOWNSEND, a citizen of the United States, residing in the city of New York, borough of Manhattan, in the county and State of New York, have invented a new, original, and ornamental Design for a Monument, of which the following is a specification, reference being had to the accompanying drawing, forming part thereof.

The figure is a perspective view of a monument showing my design.

I claim:

The ornamental design for a monument as shown.

EDWIN O. TOWNSEND.
